ATTORNEY.

UNITED STATES PATENT OFFICE.

ALEXANDER TAYLOR, OF FLUSHING, NEW YORK.

INDUCTANCE UNIT.

Application filed June 18, 1921. Serial No. 478,495.

To all whom it may concern:

Be it known that I, ALEXANDER TAYLOR, a citizen of the United States, residing at Flushing, in the county of Queens and State of New York, have invented certain new and useful Improvements in Inductance Units of which the following is a full, clear, and exact description.

This invention relates to inductance units and has particular value when these units are used in wireless telegraphy and telephony as the primary, secondary and tickler coils, which are adjustable toward and from one another in a manner well known in the art.

An object of the invention is to provide an inductance unit which will have a minimum self induction and distributed capacity and thereby a minimum radio frequency resistance, which enables more selective tuning of the coils and which has a maximum range of resonance. A further object is to provide a unit of this type which is durable, sensitive, efficient and inexpensive. Other objects and advantages will be apparent from the following detailed description of one embodiment of the invention and the novel features will be particularly pointed out in claims.

The invention comprises a comparatively thin sheet of a suitable dielectric material which acts as a form or frame upon which a conductor is wound cornerwise and alternately across opposite faces so that there will be no crossing of the conductor upon any face and the portion of the winding upon one face will be transverse to that upon the other face. By this arrangement the crossing occurs when the conductor portions are separated by the thickness of the dielectric. The sheet may have any suitable shape and preferably is provided with approximately rectangularly disposed grooves in its edges in which the conductor is wound to prevent its displacement along the edges.

In the drawing,

Fig. 1 is a front elevation of a sheet of dielectric material upon which the conductor may be wound to provide an inductance unit.

Fig. 2 is a side elevation of the same, and Fig. 3 is a front elevation of a complete unit with a single layer upon each face of the sheet.

In the illustrated embodiment of the

invention, a sheet 1 of any suitable dielectric material, such as vulcanized fibre, hard rubber, phenol condensation products, wood, porcelain, etc., is provided upon its edges 60 with shallow notches 2, which notches are approximately rectangularly disposed with respect to one another. The sheet at two adjacent corners is provided with extensions 3 and 4 carrying terminal connectors 5 and 6 to which external circuit wires 7 and 8 may be connected. From one of the terminal connectors such as 6, an insulated conductor 9 having electrical connection therewith passes toward the adjacent end of 70 an adjacent notch such as that between the extensions, and then cornerwise across one face to the further end of one of the next adjacent notches, such as at the other notch adjacent extension 3, then over the edges of 75 the sheet at that notch, then cornerwise across the other face of the sheet to the adjacent end of the next adjacent notch (proceeding peripherally in the same direction), then over the edge in the notch and 80 cornerwise across the first face and parallel with the first cornerwise stretch of the conductor, then over the edge at the notch and across the second face parallel with the other stretch upon that face to the further 85 side of the first stretch laid cornerwise, then over the edge within the notch and parallel with and along the side of the first cornerwise stretch of the conductor, proceeding as before to cause the conductor to be laid 90 progressively inward upon one face and progressively outward upon the other face. When the conductor finally reaches the end of the notch opposite that from which it originally started and adjacent the other 95 terminal connector 5 it is carried over and electrically connected to that connector so as to be placed in electrical connection with the circuit wire 7.

I have found this unit in practice to be 100 exceptionally sensitive and efficient, to decrease the self induction and distributed capacity and increase the range of resonance. The longest stretches of the conductor upon both faces are nearest the center of the 105 sheet and coil and therefore the path of the flux, which makes the unit unusually sensitive. The portion of the coil upon one face, by crossing the portion upon the other face at approximately right angles, will cut 110 the self induction approximately in half without decreasing the effect upon the same

by the flux passing through the center of the unit coil or without decreasing the flux set up by the passage of a current through the unit. With this construction the actual resistance of the coil is reduced more nearly to that of its ohmic resistance with a resulting increase in its range of resonance. If desired, more than one layer may be laid, with the layers on each face parallel or at an angle.

It will be understood that various changes in the details and arrangements of the illustrated embodiment may be made by those skilled in the art within the principle and scope of the invention.

I claim:

1. An inductance unit comprising a thin sheet of a suitable dielectric material, and an insulated conductor wound across the faces thereof with the portion of the winding upon one face extending in a direction transversely of that upon the other face.
2. An inductance unit comprising a thin sheet of a suitable dielectric material and a conductor wound as a layer across the faces thereof with the portions upon each face arranged in the same plane and substantially parallel to one another and the portion upon one face extending in a direction transversely of that upon the other face.
3. An inductance unit comprising a thin sheet of a suitable dielectric material, and a conductor wound cornerwise and alternately across the opposite faces of the sheet, the winding progressing outwardly upon one face and inwardly upon the other face.
4. An inductance unit comprising a thin sheet of a suitable dielectric material; and a conductor wound alternately across opposite faces of the sheet, the direction of winding upon one face being transverse to that of the other face.
5. An inductance unit comprising a thin sheet of a suitable dielectric material, and a conductor wound alternately across opposite faces of the sheet, the direction of winding upon one face being transverse to that of the other face, and progressing inwardly upon one face while progressing outwardly upon the other face.
6. An inductance unit comprising a thin

sheet of dielectric material, and a conductor wound as a layer alternately and cornerwise across the opposite faces of the sheet, the conductor being laid in substantially parallel positions upon each face with the direction of winding upon one face making an angle of approximately 90° with the direction of the corresponding portion of the winding upon the opposite face.

7. An inductance unit comprising a thin sheet of dielectric material, and a quadrangular winding of a conductor thereon, two opposite side portions of the quadrangular winding being disposed upon one face of the sheet and substantially parallel to one another and the other two opposite side portions of the winding being disposed upon the opposite face of the sheet and substantially parallel to one another.

8. An inductance unit comprising a sheet of dielectric material having four approximately rectangularly disposed notches in its edges, and a conductor wound in said notches and alternately across the faces of the sheet, the winding progressing inwardly upon one face while progressing outwardly upon the other face.

9. An inductance unit comprising a coiled insulated conductor having portions lying in two spaced planes, the conductor being wound alternately in said planes and the portion in each plane being transverse to that in the other plane.

10. An inductance unit comprising a coiled insulated conductor having portions lying in spaced planes, the conductor portions being wound alternately in said planes, the portion in one plane being wound progressively inward and the other portion being wound progressively outward.

11. An inductance unit comprising a coiled insulated conductor having the shape of a comparatively thin rhombohedron, the conductor being wound alternately in opposite faces of the rhombohedron, and the portion in each face being transverse to that in the other face.

In witness whereof, I hereunto subscribe my signature.

ALEXANDER TAYLOR.
